(57) **CLAIM**

The ornamental design for a display screen for testing apparatus with animated graphical user interface, as shown and described.

DESCRIPTION

This application relates to the subject matter of a design patent application identified by U.S. patent application Ser. No. 29/455,495 and filed on the same day as the instant application, the entirety of which is hereby incorporated by reference herein. Particularly, the disclaimed environment in the present application corresponds with the testing apparatus depicted in the U.S. patent application Ser. No. 29/455,495 design patent application.

FIG. 1 is the first image in a sequence for a display screen for testing apparatus with animated graphical user interface; FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof;

FIG. 19 is the nineteenth image thereof;

FIG. 20 is the twentieth image thereof;

FIG. 21 is the twenty-first image thereof;

FIG. 22 is the twenty-second image thereof;

FIG. 23 is the twenty-third image thereof;

FIG. 24 is the twenty-fourth image thereof;

FIG. 25 is the twenty-fifth image thereof;

FIG. 26 is the twenty-sixth image thereof;

FIG. 27 is the twenty-seventh image thereof;
FIG. 28 is the twenty-eighth image thereof;
FIG. 29 is the twenty-ninth image thereof;
FIG. 30 is the thirtieth image thereof;
FIG. 31 is the thirty-first image thereof;
FIG. 32 is the thirty-second image thereof;
FIG. 33 is the thirty-third image thereof;
FIG. 34 is the thirty-fourth image thereof;
FIG. 35 is the thirty-fifth image thereof;
FIG. 36 is the thirty-sixth image thereof;
FIG. 37 is the thirty-seventh image thereof;
FIG. 38 is the thirty-eighth image thereof;
FIG. 39 is the thirty-ninth image thereof;
FIG. 40 is the fortieth image thereof;
FIG. 41 is the forty-first image thereof;
FIG. 42 is the forty-second image thereof;
FIG. 43 is the forty-third image thereof;
FIG. 44 is the forty-fourth image thereof;
FIG. 45 is the forty-fifth image thereof;
FIG. 46 is the forty-sixth image thereof;
FIG. 47 is the forty-seventh image thereof;
FIG. 48 is the forty-eighth image thereof;

FIG. 49 is the forty-ninth image thereof;
FIG. 50 is the fiftieth image thereof;
FIG. 51 is the fifty-first image thereof;
FIG. 52 is the fifty-second image thereof;
FIG. 53 is the fifty-third image thereof;
FIG. 54 is the fifty-fourth image thereof;
FIG. 55 is the fifty-fifth image thereof;
FIG. 56 is the fifty-sixth image thereof;
FIG. 57 is the fifty-seventh image thereof, in accordance with one embodiment;
FIG. 58 is the fifty-seventh image thereof, in accordance with a second embodiment; and,
FIG. 59 is the fifty-seventh image thereof, in accordance with a third embodiment.

The appearance of the animated user interface sequentially transitions between the images shown in FIGS. 1-56 and ending with FIG. 57, FIG. 58, or FIG. 59. The process or period in which one image transitions to another forms no part of the claimed design. The broken line showing of the testing apparatus illustrates the environment of the claimed design and forms no part thereof.
